DESIGN FOR AN END PLATE FOR A FLUORESCENT FIXTURE

Jerome H. Steinberg, Brooklyn, N. Y.

Application December 13, 1945, Serial No. 124,700

Term of patent 3½ years

(Cl. D48—23)

To all whom it may concern:

Be it known that I, Jerome H. Steinberg, a citizen of the United States, residing at Brooklyn, in the county of Kings and State of New York, have invented a new, original, and ornamental Design for an End Plate for a Fluorescent Fixture, of which the following is a specification, reference being had to the accompanying drawing, forming part thereof.

In the drawing:

Fig. 1 is a front elevational view of an end plate for a fluorescent fixture showing my new design; and Fig. 2 is a top view thereof.

I claim:

The ornamental design for an end plate for a fluorescent fixture, substantially as shown.

JEROME H. STEINBERG.
